UNITED STATES PATENT OFFICE.

HARVEY GILES, OF BROOKLYN, NEW YORK.

TOOTHBRUSH HOLDER.

Application filed October 15, 1923. Serial No. 668,491.

The invention resides in a tooth brush holder of a character to be attached as a fixture to the wall of a bath or other room and used for holding an individual tooth-brush with the bristles thereof enclosed in a special compartment of the fixture so that the same may be protected against dust and the like and at the same time be capable of inspection through the walls of the compartment. The fixture may be equipped with one or a number of the compartments, and preferably the frame of the fixture will bear initials at the several compartments thereof as means for identifying the individual tooth brushes of the members of a family. The compartments for the individual brushes are preferably each in the form of an integral inverted glass cup vertically mounted, and the frame for the glass cups comprises a supporting base-plate, a bracket member connected therewith and to be secured against the wall and an upper member secured to the upper end of said bracket and extending forwardly to engage the closed upper end of the cup or cups, said upper member preferably being of thin sheet phosphor bronze and having an opening to receive the convex end of the cup or a plurality of such openings to engage the upper ends of the cups when more than one cup is made use of, said upper member serving to retain the cup or cups on the base-plate and to permit said cup or cups to be removed whenever it may be necessary to clean the same. The upper member of the cup holding frame is of thin spring metal and has a tension downwardly against the upper closed end or ends of the cup or cups for the purpose of detachably retaining the same in firm position and at the same time permit the cup or cups to be forced outwardly from and returned to the supporting frame whenever occasion should render that course desirable. The base frame is formed with a depressed annular socket open at its central portions and supporting a cup-shaped rubber disk having in its bottom a central opening, with slots radiating therefrom, and at its edges an upstanding annular flange closely fitting against the vertical sides of said socket, and within this socket lined with said rubber disk, is seated the inverted glass cup. The head of a tooth-brush may be forced upwardly through the rubber disk so that the bristles will be within the cup and the handle hang therefrom, the brush being supported upon the rubber disk.

The surrounding flange of the rubber disk encompasses the lower edges of the glass cup and aids in centering the cup and in avoiding fracture of the lower edges thereof.

60

The object of my invention is to provide an attractive and comparatively inexpensive brush-holder or appliance for bath-rooms and like places, and especially a brush-holder whose parts are assembled without the use of screws and in which the compartments for the brushes may be applied to and removed from the holding frame without detaching any portion of the frame.

65

The invention will be fully understood from the detailed description hereinafter presented, reference being had to the accompanying drawings, in which:

70

Fig. 1 is a central vertical section through a tooth brush holder constructed in accordance with and embodying the invention, a tooth brush being shown in position in the glass cup portion of the holder, and the section being taken on the dotted line 1—1 of Fig. 2;

75

Fig. 2 is a front elevation of the same;

Fig. 3 is a top plan view of the same;

Fig. 4 is a transverse section through the same, taken on the dotted line 4—4 of Fig. 2;

80

Fig. 5 is a detached perspective view of the rubber cup-like disk forming a seat for the lower edges of the glass cup;

Fig. 6 is a front elevation of a tooth-brush holder embodying my invention employing two glass cup compartments instead of the one glass cup compartment presented in the construction shown in Figs. 1 to 5 inclusive, and

85

Fig. 7 is a top plan view of the same.

In the drawings, referring to Figs. 1 to 4 inclusive, 10 designates an inverted glass cup compartment for the tooth brush, and 11 the supporting frame for the same, this frame comprising a base-member 12, a vertical bracket member 13 to be fastened to the wall of a room and an upper member 14 formed from a thin sheet of phosphor bronze and having in its outer portion an opening 15 of a size to receive a portion of the upper convex end of the cup 10, as shown in Figs. 1, 2 and 3, while at the same time the metal of the member 14 surrounding the opening 15 engages with a spring pressure the upper end of the cup 10 so as to hold the cup down upon the lower member 12. The members 12, 13 of the frame will 100 preferably be formed in one piece of sheet

105

110

aluminum, and the upper member 14 will preferably be secured to the upper end of the member 11 by an upturned lip 16 at the inner end of the member 14 and a turned-over lip 17 at the upper end of the member 13 and embracing said lip 16, whereby the lip 16 on the member 14 becomes pinched between the lip 17 and the upper end of the member 13, as shown in Fig. 1. The lip 16 on the bronze member 14 will preferably have two small indentures 18 forming prongs, which will enter the softer metal of the member 11 and thereby aid in rigidly securing the member 14 in position. The base-member 12 of the frame 11 is substantially horizontal and at right angles to the member 13 thereof, and said member 12 is recessed downwardly along a circular line, as at 19, to form a socket for the rubber disk 20 and lower edges of the cup 10. The base of the socket 19 is open, as at 21, so as to permit the tooth-brush to be pushed upwardly therethrough.

The rubber disk 20 is circular in outline and has an upstanding annular flange 22, and said disk has in its bottom an opening 23, from which the disk is slotted radially, as at 24. The disk 20 closely fits within the socket 19 of the frame member 12, the base of the disk fitting upon the solid walls of the bottom of the socket 19 and the flange 22 of the disk closely fitting against the inner side walls of said socket, as shown in Fig. 1.

The glass cup 10 has an open bottom and a rounded or convexed upper closed end, and the lower edges of the open bottom of the cup 10 closely fit within the flange 22 of the disk 20 and seat upon said disk around the lower edges of said flange, whereby the lower end of the cup 10 becomes not only securely held, but protected against fracture by any careless handling of the cup. The rubber disk forms a packing fully encompassing the lower edges of the cup 10. The height of the cup 10 is such that when the cup is seated in the lower member 12 of the holder, the upper member 14 of said holder will press the same downwardly with a spring pressure against said member 12, thereby maintaining the cup 10 firmly in position, at this time the upwardly convexed or reduced end of the cup 10 being projected through the opening 15 in the upper member 14, as shown in Figs. 1 and 2. When it is desired to remove the cup 10 from the holder, the upper side portions of the cup may be taken hold of between the thumb and fingers of the hand and tilted from under the upper member 14 and lifted from the member 12, the smooth upper end of the cup during the removal operation sliding under and flexing upwardly the member 14 and acting as a cam-surface against the edges of the opening 15 in the

member 14. I preferably form the upper member of thin sheet phosphor bronze, because this metal affords a spring and is very strong and durable and may be flexed upwardly by the insertion and removal of the cup 10 a great many times without becoming prejudicially affected.

In Figs. 6 and 7 I illustrate a modification of my invention in that the size of the holder is enlarged to receive a plurality of the cups 10. In Figs. 6 and 7 the holder is numbered as a whole 30 and comprises a base-member 31, a bracket member 32 and an upper phosphor bronze spring plate-member 33, these parts corresponding with the holder shown in Figs. 1 to 4 inclusive with the exception that the base member 31 has two of the sockets for the lower ends of the two cups 10 and that the upper member 33 is formed with two arms 34, 35 having openings 36 corresponding with the opening 15 in the holder shown in Figs. 1, 2 and 3 to receive the upper convex ends of the cups 10. The holder of my invention whether adapted for one tooth brush or a plurality of tooth brushes will have the same features of construction specifically shown in Figs. 1 to 5 inclusive, and therefore further detailed description of the holder shown in Figs. 6 and 7 is unnecessary. I may form the holder with provision for three, four or more cups 10, but the holding means for each cup will be the same as that shown in the drawings. When I provide a base plate 31 for a plurality of cups 10 I will form lips 37 thereon to bear initials or other marks identifying the owners of the brushes contained in the respective cups 10, as shown in Figs. 6 and 7.

It will be seen that the holder comprises few durable parts and that without the use of screws or the like the cups 10 may be applied to and removed from position whenever it may be desired to do so. The cups will be formed of reasonably thick glass, celluloid or other suitable material, so that they will not readily become fractured or otherwise injured by careless handling, and as hereinbefore described the lower free edges of the cups are protected by the cup-disk 20. One of the important features of the invention resides in the fact that the cup is spring pressed between its upper and lower ends and is removable on the flexing of the spring member 14 by the movement against the same of the upper reduced end of the cup. The holder is one of simple construction, but very desirable on account of its efficiency and neat appearance, and also because it may be constructed at small cost and sold at a minimum price.

The cups 10 constitute tubular containers for the heads of the brushes, and my invention is not limited in every respect to the form of the upper end of these containers,

since I am aware that the shape of the upper ends of the containers 10 may be modified without departing from the invention as claimed. The upper ends of the tubular containers 10 will, by preference, be wholly closed and I would regard such ends as closed even though they might contain a small vent hole 9. My experience is that the vent hole 9 is practically useless, but some others might prefer to use the vent hole and also to utilize such a hole as a means for alleging a departure from my invention.

What I claim as my invention and desire to secure by Letters-Patent, is:

1. A tooth-brush holder for attachment to a wall comprising a bracket member, a base member extending forwardly from the lower end of said bracket member, a yieldable upper member extending forwardly from the upper end of said bracket member and a tubular container held against said base member by yielding pressure of said upper member and having its lower end open to receive the head of a tooth brush, said base member having a depressed socket open at its center and a cup rubber disk thereon lining said socket at its bot-

tom and side portions and being radially slit, said socket and disk receiving the sides and edge of the lower end of said container and permitting the head of the brush to be thrust up through them to enter the container.

2. In a tooth-brush holder, the combination with a base member having a centrally apertured depressed socket, and a yieldable clamping member opposed to said socket, of a tubular container removably held between the base and clamping member, said container having a convex upper end received in an aperture in the yieldable clamping member, the lower end of the container being open and disposed within the depressed socket, and a cup rubber disk lining the annular bottom and side-walls of the socket to prevent fracture of the container when it is tilted for removal or insertion, said rubber disk being radially slit to permit the head of a tooth-brush to be passed therethrough.

Signed at New York city, in the county of New York and State of New York, this 13th day of October, A. D. 1923.

HARVEY GILES.
